PRINTING MACHINE

Clayton E. Wyrick, Wyandotte, Mich.

Original application August 29, 1936, Serial No. 98,514. Divided and this application January 3, 1938, Serial No. 183,095

11 Claims. (Cl. 101—420)

This invention relates to printing machines and particularly to the provision in web, strip or sheet printing machines, of roller means particularly adapted for supporting a freshly printed paper surface without blurring or smearing.

It is a further object of this invention to provide such supporting roller means particularly adapted for engagement with and relative movement with respect to freshly printed surfaces without blurring or smearing the ink on the supported freshly printed surfaces.

It is a further object of this invention to provide, in such structure, permanent surfaces on the roller supporting means for the achievement of the above advantages.

It is a further object of this invention to provide such structure which is of cheap and simple construction, which is durable and long-wearing and which requires no servicing or treatment during the life thereof.

These and other objects and advantages will appear from the following description taken in connection with the drawings.

This application is a division of my application Serial No. 98,514, filed August 29, 1936.

In the drawings:

Figure 1 is an elevational view of a web or strip printing machine, with attached stacker, for use in which the supporting roller of this invention is particularly adapted for use;

Figure 2 is an elevational view in section of a section of the machine showing, in end elevation, a supporting roller according to this invention in its operative relation;

Figure 3 is an elevational view of a web supporting shaft with a pair of roller means thereon, which roller means are shown in section;

Figure 4 is a similar view, but showing the web supporting shaft partly in section;

Figure 5 is an end elevation of the shaft and roller structure shown in Figure 4, as seen from the left of Figure 4, looking toward the right; and

Figure 6 is a similar view, but taken from the right of Figure 4, looking toward the left.

Referring to the drawings in detail and with reference particularly to Figures 1 and 2, the printing machine is supported on the table 1 which is supported by the legs 2 having a shelf 3 rigidly attached thereto. Rigidly attached to the under side of the table 1 is the electric motor 4 which provides power for operating the machine through the belt 5. The machine comprises a base frame generally designated 6 and a plurality of printing units generally designated 7

which are superposed thereon and which have common operative connection with the pulley 8 which is driven through the belt 5 by the motor 4. The base frame contains an aligning chamber for the webs 9 which are led therein from the pack 10 supported on the shelf 3. The aligning chamber, shown in section in Figure 2, includes the guide plate 11 over which the webs are led into the chamber and the slideable aligning frame having its side members designated 12, 10 which supports the exterior guide roller 13 and a plurality of interior guide rollers 14 having switch means associated therewith and operative upon exhaustion of the web passing about any roller 14 to cause the motor 4 to be automatically 15 stopped immediately upon exhaustion or breakage of any of the webs 9.

In Figure 2, a single, lower printing unit 7 is illustrated in section and, as therein shown, it comprises a frame having side rails 15 pivoted 20 on the brace rod 16 which has its ends secured to the sides of the base frame 6. The printing unit has a trackway 17 formed on each side rail 15 for supporting the rollers 18 and 19 of the carriage. The rollers 18 are rotatably supported upon the brace rod 20 of the reciprocable carriage, while the rollers 19 are supported upon the rod 21. Reciprocation is imparted to the carriage through the rod 21 by means of links 22 pivotally attached at one end to a rod 21 30 and pivotally attached at the other end to a sprocket chain 23 which is supported at one end by a freely rotatable sprocket and at the other end by a sprocket 24 which is fixed to the axle member 25. The axle member 25 is provided 35 with a gear 26 and is adapted for operative connection through other gearing to the motor 4.

It will thus be seen that, when the motor 4 operates, the shaft 25 is rotated to cause travel of the sprocket chain 23 which, in turn, causes 40 reciprocation of the rod 21 to which the carriage is attached. The carriage has side or end plates 27 which are secured in suitable spaced relation by means including the rod 20. The rod 21 is rotatable with respect to the side or end 45 plates 27. At its rear end, the frame of the printing unit 7 is provided with a web supporting guide roller 28 which is secured at opposite ends to the upper part of the frame and which has associated therewith brake means 29.

At the opposite end of the printing unit are guide rollers 28' non-rotatably secured to the shaft 25 and having associated therewith the roller 30 which is adapted to engage the upper surface of the web 9. Associated with this roll- 55

er 30 is brake means 31. The carriage which is generally designated 32 has thereon a swingably mounted roller 33, beneath which the web 9 is led and from thence it extends over web supporting rollers 34 which are secured, in a manner hereinafter more clearly described, to the web supporting shaft 35.

Secured to the top plate 6a of the base frame 6 is an ink fountain generally designated 36 which has therein the ink supply roller 37 adapted for controlled operation to supply a predetermined amount of ink to the ink transfer rollers 38 which are mounted in the carriage 32. Associated with ink transfer rollers 38 is the spreader roller 39 disposed therebetween and resting thereupon.

Also secured to the top plate 6a forwardly of the ink fountain 36 is the type or printing plate 40. The upper surface of the printing plate 40 forms the printing surface thereof. During the operation of the machine, the webs 9 are led over the respective guide rollers 14 in the aligning chamber and thence over guide rollers 13, guide rollers 28 and through the carriage 32, under roller 33 and over supporting rollers 34 and thence over rollers 29 and into the stacker, generally designated 41. The carriage is provided with an upwardly directed plate 42 which is adapted to cooperate with the clamping roller 43 rotatably supported at the outer end of the arms 44 which are pivotally secured to the rod 45 extending between lever arms 46 secured to the transverse rod 47.

During operation of the machine, the carriage 32 is reciprocated from left to right and then in reverse direction, as seen in Figure 2, and during the forward motion, or from left to right, the clamping roller 43 is thrust toward the plate 42 to clamp the web 9 to the carriage 32. The brakes 29 and 31 are released and as the carriage proceeds to the right, it carries the web 9 therewith, a predetermined amount, depending upon the adjustment of the releasing means for the roller 43, and then it is released.

At the end of the forward travel of the web 9 with carriage 32, the brakes 29 and 31 are set to lock the web 9 to the printing frame; and, as the roller 43 has been previously released from engagement with the paper, rearward travel of the carrier takes place independently of movement of the web 9 which is secured in stationary relation by engagement of the brakes 29 and 31 therewith. Upon the rearward movement of the carriage 32, the roller 33 is moved downwardly in such manner as to progressively press the web 9 against the upper face of the printing plate 40.

The rearward movement continues until the ink transfer rollers 38 travel over the ink supply roller 37 of the ink fountain 36. Upon the next forward movement of the carriage 32, when the web 9 is clamped thereto, and is being moved thereby, the ink is transferred from the ink transfer rollers 38 to the printing plate 40 to prepare the plate 40 for printing an impression upon the under side of the web 9 upon the succeeding rearward movement of the carriage 32.

The above description of the structure illustrated in Figures 1 and 2, and the operation thereof is deemed sufficiently to explain the relation in which the roller 34 is adapted for use. As will be understood from the above description, the rollers 34 must support the lower side of the web 9 immediately after it has been removed from engagement with the inked face of the type of the printing plate 40, during the reverse move-

ment of the carriage 32. Inasmuch as the inked impression on the lower surface of the web 9 must then be engaged by the rollers 34, it is necessary that they be so formed as to provide satisfactory support for the freshly inked surface of the web 9 without, however, causing blurring of the printing thereon.

In order that the above described support of the freshly inked surface of the web 9 be achieved, without blurring, the rollers 34 are provided at 10 each end with flanges 48 which are of triangular section, as shown in Figures 3 and 4, and which are provided with fine peripheral serrations or teeth 49. These serrations provide an interrupted annular supporting surface for engagement with 15 the freshly printed surface of the web 9, and travel of the rotatable rollers 34 over the freshly inked surface of the web 9 may, therefore, occur without blurring of the freshly inked surface. The body of the rollers 34 is cylindrical and the 20 flanges 48 at opposite ends thereof are formed integrally therewith. The central cylindrical bore 50 of the rollers is adapted for close but axially adjustable engagement with the exterior surface of the roller supporting shaft 35, and at one end 25 the rollers 34 are provided with transverse grooves or slots 51. The supporting shaft 35 is provided with an axial groove 35a extending from adjacent one end thereof to adjacent the opposite end and the extreme ends of the shaft 30 35 are reduced at 35b. These reduced ends are adapted to be rotatably supported in the side or end plates 37 of the carriage 32.

In order to provide for adjustably supporting the rollers 34 on the shaft 35, a flat spring member 52 is provided, which has each end 53 thereof turned upwardly and the central portion 54 thereof bowed. One end portion 53 of each spring member 52 is adapted for disposition in a groove 51 in the roller 34, while the central bowed portion thereof is adapted for engagement with the bottom of the groove 35a in the shaft 35. The opposite end 53 is adapted to closely engage the opposite end of the roller 34. The spring member 52, in cooperation with the slot 35a, thus provides means for securing the roller 34 to the shaft 35 against rotation with respect thereto, while resiliently maintaining the roller 34 in adjusted position axially of the shaft 35. The rollers 34 are thus axially adjustable on the shaft 35 and non-rotatable with respect thereto.

As above described, the provision of the serrations 49 on the flanges 48 thereof provide interrupted surfaces engageable with freshly inked surfaces to support the freshly inked surfaces without blurring thereof. The triangular annular sections of the flanges 48 with the serrations 49 form spaced radial tooth surfaces which remain permanently operative to achieve the above described advantages throughout the life of the roller. As the roller is formed of suitable metal such as iron, steel, bronze, brass or the like, the life thereof is, therefore, substantial.

Due to the fact that the serrated surfaces of the rollers 34 are movable over the paper surfaces of the webs 9, or vice versa, there is no appreciable friction created therebetween and, therefore, no appreciable wearing away of the serrated surfaces of the roller 34.

It is, of course, to be understood that the above-described use of the principles of this invention is merely illustrative and that the principles thereof may be applied to various widely different structures for the achievement of the above advantages, whether the machines be

printing machines, multigraphing machines or the like, or typewriting machines, where it is desired to avoid blurring on surfaces recently printed or provided with legible or visible impressed or otherwise applied characters, designs or the like.

It is furthermore to be understood that, while the roller of this invention has been described as formed of metal, it may be formed of other ink resistant materials such as hard rubber, phenolic condensation products, synthetic resins or the like and, where desired, of other various non-rigid or resilient materials.

It will be understood that the above-described structure is merely illustrative of the manner in which the principles of my invention may be utilized and that I desire to comprehend within my invention such modifications as come within the scope of the claims and the invention.

Having thus fully described my invention, what I claim and desire to secure by Letters Patent is:

1. A non-smear member for engaging and supporting a wet inked web surface comprising a roller having a plurality of axially adjustable surface portions with fine radially disposed teeth thereon for providing an interrupted annular supporting means for said wet inked web surface.

2. A non-smear member for supporting a wet inked surface comprising a roller shaft having enlarged spools mounted thereon and provided on their peripheral surfaces with fine serrations, said spools being axially adjustable.

3. As an article of manufacture for use as a non-smear paper supporting roller, a cylindrical body slidably and yieldably secured to a central axle and having an integral enlarged serrated flange, said serrations being spaced from the body thereof to provide spaced pointed supports for said paper.

4. As an article of manufacture for use as a non-smear paper supporting roller, a cylindrical metal body having spaced integral enlarged finely toothed flange means with the teeth thereon disposed radially and extending outward from the body thereof, said body being resiliently attached to an axle shaft so as to be adjustably retained thereon.

5. Non-smear supporting means for wet inked surfaces comprising a rotatable supporting shaft, a spool member thereon non-rotatable with respect thereto and axially adjustable thereon, and having annularly disposed fine peripheral serrations on said spool member spaced from the body thereof and supportingly engaging the wet inked surface.

6. Non-smear supporting means for wet inked paper surfaces comprising a rotatable supporting shaft, a plurality of spools axially adjustable and yieldably mounted thereon, and outwardly extending annular toothed surfaces on the outer edges of said spools spaced from the bodies thereof and supportingly engaging the wet inked surface.

7. Non-smear supporting means for wet inked

paper surfaces comprising a freely rotatable supporting shaft having axial grooved means therein, a cylindrical roller member having integral finely toothed flange means and having a central bore receiving said shaft, and a spring member disposed in said bore, extending into said groove for frictional engagement with a wall thereof and rotatably secured at one end to said roller.

8. Non-smear supporting means for wet inked paper surfaces comprising a freely rotatable supporting shaft with an axial groove therein, a plurality of cylindrical roller members with integral, outwardly extending finely toothed flange means and a central bore receiving said shaft, and spring members in said bore extending into said groove and frictionally engaging a wall thereof, said spring members each having one end non-rotatably secured to an end of a roller.

9. In a printing machine comprising a printing plate, carriage means reciprocable above said plate and means on said carriage for progressively engaging a paper strip with said printing plate, the improvement which consists in providing a non-smearing supporting means for the wet ink paper surfaces, said supporting means comprising a freely rotatable supporting shaft having axial groove means therein, a cylindrical roller member having integral finely toothed flange portions and provided with a central bore for receiving said shaft on which is mounted a spring member disposed in said bore and extending into said groove for frictionally engaging with a wall portion thereof and rotatably secured at one end to said roller.

10. In a printing machine comprising a printing plate, carriage means reciprocable above said plate and means on said carriage for progressively engaging a paper strip with said printing plate, the improvement which consists in including a non-smearing supporting means for the wet inked paper surfaces, said supporting means comprising a freely rotatable supporting shaft with an axial groove therein, a plurality of cylindrical roller members with integral outwardly extending finely toothed flange means thereon and a central bore for receiving said shaft, and spring members in said bore extending into said groove and frictionally engaging the wall portion thereof.

11. In a printing machine comprising a printing plate, carriage means reciprocable above said plate and means on said carriage for progressively engaging a paper strip with said printing plate, the improvement which consists in including a non-smearing supporting means for the wet inked paper surfaces, said supporting means comprising a cylindrical body having a spaced integral enlarged finely toothed flange means with the teeth thereon disposed radially and extending outwardly from the body thereof and wherein said body is slidably longitudinally of a supporting shaft for axial adjustment.

CLAYTON E. WYRICK.
